UNITED STATES PATENT OFFICE

JOHN H. WELLER, OF NEW HAVEN, CONNECTICUT, ASSIGNOR TO SARGENT & COMPANY, OF NEW HAVEN, CONNECTICUT

FIBER BEARING BUTT HINGE

Application filed January 7, 1930. Serial No. 419,053.

This invention relates to hinges and more particularly to that type of same usually referred to as butt hinge, such as is commonly used in connection with the hanging of doors. As usually made, such hinges comprise a pair of leaves attached to the door frame and door respectively, the leaves being provided with knuckles having aligned openings through which a hinge pin is passed, the door swinging about the axis of this pin. Such hinges are subject to the disadvantage of rusting or corroding so that they work less easily than when in good condition and also particularly in the case of heavy doors the parts develop considerable friction so that it is advantageous to place an anti-friction bearing between the knuckles which will take the weight of the door and reduce the friction between parts.

One object of this invention is to overcome the disadvantage referred to above and provide a door hinge which will operate easily at all times and be practically noiseless in operation.

A further object of the invention is to provide a hinge of this character with anti-friction bearings which bear the weight of the door so that the parts of the hinge will move with greater freedom.

Another object of the invention is to provide a fibre bearing for a door hinge of this character so that the parts will operate with less friction and the bearing itself will be durable and economical to manufacture.

To these and other ends the invention consists in the novel features and combination of parts to be hereinafter described and claimed.

In the accompanying drawing:

Fig. 1 is an elevated view of a hinge in open position embodying my improvements;

Fig. 2 is a sectional view through the hinge pin;

Fig. 3 is an enlarged fragmental sectional view through the knuckle to which the bearings are attached;

Fig. 4 is a composite view showing the manner of assembly of the parts, and,

Fig. 5 is a view similar to Fig. 3 showing a modification.

To illustrate a preferred embodiment of my invention, I have shown a hinge comprising a pair of leaves 10 and 11, one of which is adapted to be secured to the door frame and the other to the door. The leaf 10, as shown, is provided with the knuckles 12, 13, and 14, and the leaf 11 with the knuckles 15 and 16 which are adapted to be received between the knuckles on the leaf 10. All of the knuckles, as shown on Fig. 2, are provided with aligned openings through which may be passed the hinge pin 17 to secure the two parts of the hinge together. In the usual form this hinge pin may be readily removed so that the two parts of the hinge may be detached.

It will be apparent that in the form of my invention shown, the knuckle 13 is of less height than the other knuckles and upon each end of knuckle 13 is mounted a bearing unit, one of which is adapted to receive the weight of the door depending upon the position in which the hinge is used. These bearing units are alike and one only thereof will be described.

These bearings comprise a cup shaped container having a side wall 18 and a bottom wall 19, the bottom wall having a central opening for a passage of the hinge pin. Within this container are mounted a pair of hardened steel washers, 20 and 21, one of which is adjacent to the upper end and the other adjacent the bottom of the container. It will be noted that the peripheral edge of the upper or outer washer 20 is somewhat tapered in shape so that the upper edge of the side wall 18 of the container may be displaced and crimped inwardly to secure the washer 20 in place.

Between the washers 20 and 21 is placed a washer 22 which I prefer to form of fibre. This fibre washer 22 is placed between the hardened steel washers and may be lubricated with a dry lubricant, as graphite or the like, which will prevent any tendency of the adjacent surfaces of the steel washers to rust, and at the same time to provide for free turning of all of the washers relatively to each other. It will, of course, be understood that the washers are assembled within

the container with sufficient freedom so as to permit of this turning movement. The fibre washer 22 when placed between two hardened washers in this manner, provides 5 a bearing which operates with extremely little friction and one which is very durable, being able to withstand a great deal of use without having to be replaced.

It will be noted that the upper washer 20 10 projects slightly above the side wall 18 of the container so that the adjacent knuckle of the companion leaf of the hinge rests upon this washer and will not bear against the container which may not always be free 15 to turn.

If it is desired to secure the bearing to the hinge knuckle, this may be effectively done by passing a tubular sleeve member 23 through the bore of the knuckle, around the 20 hinge pin 17 and securing the ends of this sleeve to the lower portion of the bearing unit. The ends of the sleeve are secured to a portion of the unit below all of the bearing washers so that all of the latter are left 25 free to turn.

In the form of my invention shown in Fig. 3, the bottom portion 19 of the container is relatively thin and I find it desirable to place adjacent to bottom 19 an additional washer 24. The opening through this washer is slightly beveled outwardly and upwardly as shown in 25.

The unit consisting of the container and the four washers, 20, 21, 22, and 24 may be 35 slipped over the sleeve 23 after the latter has been placed within the knuckles and the end of the sleeve entering the container is then expanded over the lower washer 24 and the bottom of the container. The use of the 40 washer 24, which may be made of steel, affords reinforcement for the relatively thin bottom 19 of the container, and when the end of the sleeve 23 is expanded over the beveled edge 25, this provides a secure method 45 of fastening the bearing in place. The lower bearing washer 21 may be provided with a counter-bore 26 which faces downwardly so that the washer will clear the expanded end of the sleeve 23 to prevent 50 friction between the parts.

In Fig. 5 of the drawing, I have shown a somewhat modified form of the invention in which the washer 24 is omitted. The bearing unit in this instance comprises the 55 container having the side wall 18^a and a relatively thick bottom wall 19^a within the container, and the washers 20^a, 21^a and 22^a, which are similar in all respects to the corresponding parts shown in Figs. 1 to 4. In 60 this form of the invention, the outer ends of the sleeve 23^a are expanded over the beveled edge of the opening in the relatively thick bottom 19^a of the container. When 65 the bottom of the container is made relatively heavy and strong, as in this form of

my invention, the additional washer 24 may be omitted. The operation of this form of the invention is, however, precisely the same as that of the form shown in Figs. 1 to 4.

It will be apparent that when the sleeve 70 23 (or 23^a) is secured to the bearing unit below the bearing washers, all of the three washers are left free to turn as such movement is required, and should any of these washers tend to turn with the hinge pin, 75 they will be permitted to do so without any friction with the securing sleeve.

While I have shown and described some preferred embodiments of my invention, it 80 will be understood that it is not to be limited to all the details shown, but is capable of modification and variation within the spirit of the invention and within the scope of the appended claim.

What I claim is:—

A hinge having a knuckle, a bearing container positioned on said knuckle, a washer within said container and over-lying a part thereof, a sleeve passing through the bore of the knuckle and engaging said washer to 90 retain the container on the bearing and bearing members within said container above the washer.

In witness whereof, I have hereunto set 95 my hand this 26 day of December, 1929.

JOHN H. WELLER.
